UNITED STATES PATENT OFFICE.

ANDREW A. KRAMER, OF KANSAS CITY, KANSAS.

SHEET-METAL BUILDING.

1,229,478.

Specification of Letters Patent. Patented June 12, 1917.

Application filed July 21, 1916. Serial No. 110,501.

To all whom it may concern:

Be it known that I, ANDREW A. KRAMER, a citizen of the United States, residing at Kansas City, in the county of Wyandotte and State of Kansas, have invented certain new and useful Improvements in Sheet-Metal Buildings; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to sheet metal buildings and has for its object to provide a building of this character which may be used as a garage for the storage of implements or of vehicles and which is weather-proof and substantially rigid.

It is also an object of the invention to provide a box joint structure which may be bent at the corners of the building and ridge 25 of the roof without splitting or breaking the box rib.

A further object of the invention is to provide a structure of this character having an eaves trough for conducting water across 30 the door openings.

In accomplishing these objects I have provided the details of structure hereinafter described and illustrated in the accompanying drawings, wherein:—

35 Figure I is a perspective view of a sheet metal building constructed according to my invention.

Fig. II is an interior perspective view of one of the compartments, particularly illustrating the door sections and their mounting.

40 Fig. III is a detail perspective and sectional view of the trough and corner portion of the building.

45 Fig. IV is a sectional view through the door, trough and roof section, on the line IV—IV, Fig. I.

Fig. V is a horizontal section through a door and panel section.

50 Fig. VI is a horizontal section illustrating a box joint.

Referring more in detail to the drawings:

1 designates the building as a whole, which comprises the sides 2, roof 3, rear 55 wall 4, doors 5, division walls 6 and windows 7, all of which, except the windows,

are constructed of sheet metal and combined to form a building structure. The side wall and roof members are made up, of separate sections and provided with box 60 ribs 8, which are formed in a press and comprise outstanding ribs preferably square in cross section and all of the same dimensions, so that a rib of one section may be spread over a rib of an adjoining section 65 and be bolted thereto to form a joint; a rib being formed along each longitudinal edge of each strip so that joints may be formed at the meeting edges of the strips.

The roof 8 is also formed in sections of 70 the same width as the side sections so that they may rest thereover to form joints in the same manner as the joints are formed in the side walls, the roof sections being arched at the center and curved downwardly at the 75 edges to overlap the wall sections, and form extensions thereof, and are connected therewith by bolts 10, or the like, to form an integral structure.

In order to stiffen the wall and roof sections I preferably corrugate the strips transversely, the corrugations not only serving to form a rigid structure, but also making it possible to bend the sections so that the ridge and edge turns may be made on the 80 roof sections, it being apparent that the presence of the box rib would render it difficult to effect the bend without some means of expansion being provided, and it being further apparent that with the sections or 85 strips of metal corrugated prior to the formation of the ribs, when the sheet is bent, the extra metal provided by the corrugations will enable the ribs to straighten out 90 and thereby effect the bend.

The back 4 and end walls 2 of the building are preferably formed of continuous vertical strips of the corrugated or box ribbed metal, which are bolted at their upper ends to the roof sections, so that there 95 is no break between the roof and ground, but the front of the building, except for division panels 12, which are joined with the partitions 6, is left open and each compartment in the structure formed within the 100 building by the division walls is provided with the separate doors for closing the compartments. The doors 5 are made up of separate sections, preferably three in number, which are hingedly connected and 110 adapted to swing inwardly, the said door sections being supported by hangers 14

from a track 15 which is fastened by bolts 16 to the down turned portions of the roof above the door line and is curved adjacent the partition walls 6 and continued therealong toward the rear of the building.

The hangers 14 for the doors comprise rollers 16' which are carried in a bracket 17 which has a depending portion 18 to which the door hanger 19 is pivotally suspended, 10 so that to open the building the hinged door sections 5—5'—5" may be moved along the track and will follow along the curved portion of the track and toward the rear of the building along the partition wall.

15 I also prefer to suspend the door from two end sections leaving one section free to swing so that if it is not desired to open the entire door the free section may be swung inwardly to admit a person; the free door sections being provided with hasps 20 by which the doors may be locked to the panels 12 to hold the doors closed.

20 The panel section 12 adjacent the opening edge of the door section 5" is provided with a back turned portion 22 and an inturned flange 23 against which the door edge may seat, and at the opposite side of the opening I provide the panel 12' with a portion 24 turned back on the body portion, an out-turned portion 25 and a forwardly extending flange 26 forming a socket 27 within which the rear sections of the door may seat when the doors are in closed position, thereby locking the door so that it cannot be pushed inwardly and also making it weather-proof. The two forward sections of the doors 5 are provided at their outer hinged edge with flanges 28 which overlie the faces of adjoining sections to effectively close the 40 joints therebetween against the weather.

45 Extending across the front of the entire building above the door line, I provide an eaves trough 30 whereby water may be conducted across the door openings, the trough comprising an extended upstanding back portion 31, which is projected back of the down-turned edges of the roof sections and is bolted thereto by bolts 32, and has a base 33 and an upturned outer wall 34 which is 50 of less height than the rear back portion 31, and has an outturned stiffening flange 35.

55 In order to further stiffen the down-turned portions of the roof sections at the front and back of the building, I provide a large corrugated rib 36 which extends the entire length of said downturned portions and the back sections 4 and the back portion 31 of the trough 30 are likewise provided with corrugations 37—38 adapted for seating within the corrugations of the roof members, so that when the two are bolted together they are substantially stiffened and no additional bracing is necessary.

55 The trough is extended beyond the wall at one end of the structure and is provided

with a brace 40 and has an opening 44 therein for receiving a drain spout to conduct the water to the ground, or away from the building.

In order to further stiffen the side walls 70 and prevent water from running thiereunder I provide a seat 42 which preferably consists of an angle iron to which the lower edges of the wall sections may be bolted, and having a base section which is extended outwardly beyond the walls which may be bolted or otherwise secured to a base or foundation.

75 The windows 7 may be of any suitable type, those herein illustrated comprising 80 circular openings equipped with pivotally mounted panes 45 which may be swung inwardly and outwardly within the opening.

85 The partition walls 6 are of the same general construction as the outer walls and are bolted to the rear wall, the central front panel 12, and to the roof section, thereby serving as a tie for those parts and acting 90 as a stiffening and supporting member for the roof sections.

95 In manufacturing the building, sheet metal strips of proper width are run through a corrugating machine to form the transverse corrugations. They are then worked on a press to form the longitudinal box ribs. The roof sections are then shaped on a suitable form, the transverse corrugations on the roof sheet strips enabling the metal to be bent to form the end curves and the center ridge.

100 When the building is erected, the side wall and roof sections are bolted together to form an integral structure. The eaves trough is then bolted beneath the port edge of the roof sections and the dividing partition bolted to the wall and roof sections. The track is then hung to the front portions 105 of the roof sections and to the partition wall and the doors hung thereon.

110 It is apparent that a building of this construction may be manufactured at a small cost and will afford a substantial structure within which to house vehicles or implements, and that by the addition of roof and wall sections and by placing additional division walls, a structure of any desired number of compartments may be provided.

115 Having thus described my invention, what I claim as new therein, and desire to secure by Letters-Patent, is:—

120 1. In a building having a side opening and a wall member having a lower edge terminating above the opening, a trough having an inner wall member lying along the inner face of the building wall member and attached thereto, whereby the trough is supported from the building wall member and the said building wall member projected into the trough substantially as set forth.

125 2. In a building having a side opening 130

and comprising a wall member having a free edge terminating at the top of said opening, and having a transverse corrugation adjacent said free edge, a drain trough having 5 a rear wall lying along the inner face of said building wall and having a corrugation seated within the corrugation of said side wall, and means for attaching the rear wall of the trough to the side wall of the building, whereby the trough is supported from 10 the side wall, with the lower edge of the side wall located within the trough for the purpose set forth.

3. In a building having a side opening 15 and comprising a side wall member having a free edge at the top of the opening, a door hanger carried by the side wall, a door carried by said hanger, a trough having a rear wall lying along the inner face of said wall 20 member and bridging the space between said

side wall member and the suspended door, and means for attaching the rear wall of said trough to the side member of the building.

4. In a building comprising a side opening and a roof provided with a downturned portion, forming a part of the side wall of the building and having a free edge terminating at the top of said opening, a hanger carried by the said downturned roof portion, a door carried by said hanger, and a trough having a rear wall projected between the side wall member of the building and said door and attached to the side wall member whereby the door may move 30 along the inner wall of the trough and the side member drain into said trough substantially as set forth.

In testimony whereof I affix my signature.
ANDREW A. KRAMER.
